W. D. BREWSTER

CAR BRAKE OPERATING MECHANISM

Filed July 18, 1923

FIG. 1.

FIG. 2.

FIG. 3.

INVENTOR
W. D. Brewster
By Howard P. Dimon
ATTORNEY

UNITED STATES PATENT OFFICE.

WILLIAM D. BREWSTER, OF SYRACUSE, NEW YORK, ASSIGNOR TO NATIONAL BRAKE COMPANY, INC., OF BUFFALO, NEW YORK, A CORPORATION OF NEW YORK.

CAR-BRAKE-OPERATING MECHANISM.

Application filed July 18, 1923. Serial No. 652,283.

To all whom it may concern:

Be it known that I, WILLIAM D. BREWSTER, a citizen of the United States of America, of Syracuse, in the county of Onondaga, in the State of New York, have invented new and useful Improvements in Car-Brake-Operating Mechanism, of which the following, taken in connection with the accompanying drawings, is a full, clear, and exact description.

This invention relates to a hand operated brake mechanism adapted to be used more particularly on the upright end walls of box cars with the hand wheel or other operating member at the outside or at the inside of said wall.

The main object is to inclose the major portion of the mechanism within the wall leaving only the operating member exposed and thereby to protect such mechanism against accumulations of snow, ice and other foreign matter which might interfere with its free operation.

Another object is to provide external means for forcing the holding pawl or detent to and from its holding position, and to provide said means with suitable indicia to indicate the position of the pawl.

Other objects and uses relating to specific parts of the device will be brought out in the following description.

In the drawings,

Figure 1 is an end face view, partly in section, of a brake mechanism embodying the various features of my invention exclusive of the wall in which it is placed.

Figure 2 is a vertical sectional view of the same device taken on line 2-2, Figure 1, showing the inner and outer sides of the end wall of a car in which the major portion of the mechanism is inclosed.

Figure 3 is an enlarged detail sectional view taken in the plane of line 3-3, Figure 2, showing more particularly the operation of the holding pawl or detent.

As illustrated, this device comprises a main supporting frame consisting of inner and outer upright bars —1— and —2— held in spaced relation throughout the major portions of their lengths by lower and upper cross bars —3— and —4— which may be cast integral with the side bars —1— and —2— to form an open frame of relatively light but strong and durable construction and of substantially uniform horizontal

depth for securement in an upright position between the opposite upright sides as —a— of one of the end walls —A— of a box car.

The lower end of the frame is secured to and between the side —a— by means of a 60 clamping bolt —5— which is passed through registering openings in the frame and end wall of the car.

The upper portion of the frame is provided with opposite laterally extending lugs 65 or ears —6— for receiving similar clamping bolts which are passed through the frame and end wall of the car in a manner similar to that shown at the lower end of the frame.

An operating shaft —8— is journaled in suitable bearings —9— in the opposite upright bars —1— and —2— in approximately the same horizontal plane as the clamping bolts —7— and has one end provided with a nut —10— and washer —11— for holding it against endwise displacement in one direction, the nut —10— being adapted to abut against the inner face of the adjacent sides to hold the shaft against 70 movement in the opposite direction.

The other end of the shaft extends some distance beyond the adjacent wall and is provided with a hand wheel —12— secured thereto by a key —13— and nut —14— to 75 firmly lock the wheel to the shaft.

A pinion —15— is keyed or otherwise secured to the intermediate portion of the shaft —8— between the upright bars —1— and —2— and meshes with a relatively 80 larger underlying gear —16— which is journaled on the intermediate portion of a supporting pin —17— having its end secured in suitable openings in the opposite bars —1— and —2—.

A pinion —18— is also mounted upon the cross pin —17— at one end of the gear —16— and preferably integral therewith and meshes with a relatively larger gear which is journaled on a supporting pin —20— having its ends secured in suitable openings in the opposite bars —1— and —2—, as shown in Figure 2.

A sprocket wheel —21— is revolvably mounted on the spindle —20— at one end of 105 the gear —19— and preferably integral therewith so that both may rotate together, said sprocket wheel being of relatively small diameter as compared with that of the gears —16— and —19—.

A sprocket chain —22— is attached at one end by a pivotal bolt —23— to the lower end of the frame below the bolt —5— and has its intermediate portion riding over and upon the sprocket wheel —21— and its other end adapted to be connected in any well known manner to the brake shoes of the car not shown, whereby the rotation of the sprocket wheel in the direction indicated by the arrow in Figure 1 will cause the application of the brake shoes to the wheels of the cars, while the reverse movement of the sprocket wheel will relax the brake shoes.

15 The ratio of the gears —15—, —16—, —18— and —19— and sprocket wheel —21— is such as to cause the brakes to be applied with considerable force by the application of a relatively small amount of power to the 20 hand wheel —12—.

A holding pawl or detent —24— is keyed or otherwise secured to the intermediate angular portion of a sleeve —25— having its opposite ends journaled in suitable bearings 25 in the upper portion of the main supporting frame to permit the pawl to be rocked into and out of engagement with the teeth of the gear —16—.

That is, the sleeve is journaled in the 30 frame above the operating shaft —8—, while the pawl extends across the periphery of the gear —15— and has its free end movable into and out of engagement with the teeth of the gear —16—, one end of the 35 sleeve being provided with an annular flange —26— abutting against the outer face of the adjacent bar —2—.

A bolt —27— is passed through the sleeve to hold it in place and has its end adjacent 40 to the flange —26— reduced for receiving one end of a radially extending arm —28— having its other end weighted at —29— and provided with the indicia words "On and Off".

45 The flange —26— is provided with stop shoulders —30— at opposite sides of its axis of movement and in the path of movement of the arm —28— so that when the arm is rocked into engagement with one of 50 said stops, its weight will rock the sleeve —25— in one direction to cause the pawl —24— to engage the teeth of the gear —16— for locking the gears against rotation, in which position, the word "On" will appear 55 at the top of the weighted member —29—.

On the other hand, by rocking the arm —28— from that position through an arc of approximately 180°, its weighted member will engage the other stop —30— and thereby rock the sleeve —25— to force the pawl —24— out of engagement with the teeth of the gear —16— and in this position, the word "Off" will appear at the top of the weighted member —29—.

60 The weighted pawl operating member

—28— and lugs —30— are exposed to the exterior where the indicia on the weighted ends —29— are readily visible to indicate the position of the pawl which, with the several gears and sprocket gears are located between the bars —1— and —2—, and therefore within the wall —A—, the same being also true of the sprocket chain —22— except that portion which extends below the bottom of the car for connection with the 75 shoes.

When the pawl —24— is released, the hand wheel —12— and the several gears together with the sprocket wheel —21— may be rotated in either direction to impart the desired tightening or loosening movement of the chain —22— and when the brakes are set by the proper operation of the hand wheel, —12—, the operating mechanism may be set or held in their adjusted positions by the 85 engagement of the pawl —24— with the teeth of the gear —16—.

The position of the pawl may be varied by throwing the weighted arm —28— against one or the other of the lugs —30— to impart a sufficient rocking movement to the sleeve —25— to throw the pawl to and from its locking position, as indicated by the indicia on the weighted member —29—.

The term "box car" herein referred to is 95 used in its broadest sense to include any car having upright end walls within or upon which the mechanism forming the subject matter of my present application is mounted in such manner that the slack of the 100 brake operating chain is free to rise and fall as the brake is tightened and loosened by the operation of the sprocket wheel which supports the chain.

I claim:

1. In a brake operating mechanism for box cars, in combination with one of the end walls of the car, an upright frame secured to and between the inner and outer sides of said wall, a sprocket wheel journaled in said frame, an operating shaft journaled in the frame above the sprocket wheel and provided with a hand wheel, a sprocket chain passed over the sprocket wheel and having one end attached to the lower portion of the frame and its other end adapted to be connected to a brake mechanism, means for transmitting rotary motion from the operating shaft to the sprocket wheel, and means including a pawl for cooperating 110 with a part of the last named means for holding the operating shaft against rotation.

2. A brake operating mechanism, as in claim 1, in which means is provided operable at will for shifting the pawl to and from its holding position.

3. A brake operating mechanism, as in claim 1, in which the pawl is mounted upon a rocking member having stop shoulders at

opposite sides of its axis of movement, and
a weighted member movable at will into and
out of engagement with either of said stops
for rocking the pawl to and from its hold-
ing position, said weighted member being
provided with indicia to indicate the posi-
tion of the pawl.

In witness whereof I have hereunto set
my hand this 2nd day of July 1923.

WILLIAM D. BREWSTER.
